UNITED STATES PATENT OFFICE.

PAUL MAUSER, DECEASED, LATE OF OBERNDORF-ON-THE-NECKAR, GERMANY, BY FRIEDRICH EICHORN, ADMINISTRATOR, OF OBERNDORF-ON-THE-NECKAR, GERMANY, ASSIGNOR TO WAFFENFABRIK MAUSER AKTIENGESELLSCHAFT, OF OBERNDORF-ON-THE-NECKAR, GERMANY, A CORPORATION OF GERMANY.

ROTATABLE BREECH-BOLT FOR AUTOMATIC FIREARMS.

1,180,784.

Specification of Letters Patent. Patented Apr. 25, 1916.

Application filed December 1, 1914. Serial No. 875,051.

To all whom it may concern:

Be it known that PAUL MAUSER, deceased, late a subject of the King of Wurttemberg and residing at Oberndorf-on the Neckar, in the Kingdom of Wurttemberg, Germany, invented certain new and useful Improvements in Rotatable Breech-Bolts for Automatic Firearms, of which the following is a specification.

10 This invention relates to a further development of the rotatable breech bolt for automatic fire arms with fixed barrel shown in an application of the said Paul Mauser filed February 12, 1914, Serial No. 818,235, 15 wherein a positive locking is attained in that the breech bolt having the nipples cooperates with a longitudinally movable locking part, which in the locking position and by the controlling of the nipples locks 20 the breech bolt against rotation and is released from its locking position only by the shot.

The subject matter of the present invention relates to the arrangement wherein the locking part does not lock the breech bolt directly but through the medium of a pawl inserted between the locking part and the breech bolt, such pawl in its inner position controlling the movement of the bolt nipples 30 and being positively rocked inwardly and outwardly by the locking part in its longitudinal movement.

This improvement is shown in the accompanying drawing.

35 Figure 1 is a plan of the breech bolt with its parts in the locking position, the pawl being disposed inwardly and the rod controlling the movements of the pawl in the locking position. Fig. 2 is a front elevation. 40 Fig. 3 is a side elevation to Fig. 1. Fig. 4 shows the position after the shot with outwardly disposed pawl and advanced rod. Figs. 5 and 6 are plan and interior views respectively of the sliding control-rod.

45 According to this invention, the breech bolt *k* carries the bolt head *v* with the rotatable or locking nipples *w*, while the locking parts, which effect the positive locking, coöperate with the bolt head *v*. For the 50 maintenance of the gas-tight breech bolt while the projectile is still in the barrel, there is provided a pawl *t* which is pivoted

behind the bolt head to the breech bolt and is controlled in its action by the longitudinally movable rod *s*. In the locking position of the parts *i. e.* before and during the firing, the nipple *w* is controlled by the front arm of the pawl provided with a bevel *t'*; the rod *s* is now in the rearward position, so that it secures with its inwardly bent head *s'* the arm of the pawl in its controlling position. The rear arm of the pawl *t* has a projection *t''*, which bears within a longitudinal recess *s''* of the rod *s*. If, after the firing, the rod *s* advances through its inertia, its head *s'* will release the arm of the pawl; owing to the action of the cam surfaces in the recess *s''* of the rod *s* on the projection *t''* of the rear arm of the pawl, the pawl is actuated in such a manner that its front 70 arm is rocked outwardly clear of the nipple *w*, whereby the bolt head is released for rotation. The projectile has then left the barrel and the unlocking as well as the backward movement of the breech bolt can take 75 place normally under the action of the existing pressure. The rod *s* is provided with an upwardly disposed push button *s^o* for being operated by hand when loading for the first time so that the advancement of 80 the rod *s* and the return of the breech bolt can be effected by a grip with the right hand.

What is claimed is:

1. A breech mechanism for fire arms, comprising a breech piece, said breech piece having a rotary part having locking lugs thereon, and means for locking said breech piece in position to close the breech, said means comprising a part on said breech piece 90 adapted to move into and out of position to prevent rotation of said rotary part, and an inertia piece adapted to retain said locking part on the breech piece in locking position.

2. A breech mechanism for fire arms, comprising a breech piece, said breech piece having a rotary part having locking lugs thereon, and means for locking said breech piece in position to close the breech, said means comprising a part on said breech piece 100 adapted to move into and out of position to prevent rotation of said rotary part, and an inertia piece adapted to retain said locking part on the breech piece in locking posi-

tion, said inertia piece being adapted to move on recoil of the fire arm out of retaining position.

3. A breech mechanism for fire arms comprising a casing having inclined grooves, a breech piece, said breech piece having a rotary part having locking lugs thereon, and means for locking said breech piece in position to close the breech, said means comprising a part on said breech piece adapted to move into and out of position to prevent rotation of said rotary part, and an inertia piece adapted to retain said locking part on the breech piece in locking position, said inertia piece being adapted to move on recoil of the fire arm out of position to retain said locking part on the breech piece in locking position, and the incline of the grooves being such that the pressure of the gas in the fire arm is sufficient to turn said rotatable part of the breech piece in said inclined grooves and open the breech.

4. A breech mechanism for fire arms including a breech piece, said breech piece having a rotary part having lugs thereon, and means for locking said breech piece in position to close the breech, said means comprising a part pivotally mounted on the breech piece adapted to move into and out of position to prevent rotation of said rotary part, and an inertia piece adapted to retain said pivotally mounted part in locking position, said inertia piece being adapted to move on recoil of the fire arm out of retaining position.

5. A breech mechanism for fire arms comprising a breech piece, said breech piece having a rotary part having locking lugs thereon and means for locking said breech piece in position to close the breech, said means comprising a two-armed lever pivotally mounted on the breech piece, one arm of which is adapted to move into and out of position to prevent rotation of said rotary part, and an inertia piece adapted to retain said lever in locking position, said inertia piece on recoil of the fire arm being also adapted to contact with one arm of said lever to move said lever out of locking position.

6. A breech mechanism for fire arms comprising a breech piece, said breech piece having a rotary part having locking lugs thereon, and means for locking said breech piece

in position to close the breech, said means comprising a part on said breech piece adapted to move into and out of position to prevent rotation of said rotary part.

7. A breech mechanism for fire arms comprising a breech piece, said breech piece having a rotary part having locking means thereon, and means on said breech piece for locking said rotary part against rotation.

8. A breech mechanism for fire arms comprising a breech piece, said breech piece having a rotary part having locking means thereon, and means on said breech piece for locking said rotary part against rotation, and an inertia part controlling the action of said locking means.

9. A fire arm comprising a breech bolt having a rotatable part, and means for preventing rotation of said rotatable part, said means comprising a pawl adapted to engage the rotatable part and an inertia part controlling the action of said pawl.

10. A fire arm comprising a breech bolt having a rotatable part, and means for preventing rotation of said rotatable part, said means comprising a pawl adapted to engage the rotatable part and an inertia slide having a projection adapted to engage behind said pawl and adapted to move from behind said pawl under the force of inertia.

11. A fire arm comprising a breech bolt having a rotatable part, and means for preventing rotation of said rotatable part, said means comprising a pawl adapted to engage the rotatable part and an inertia part controlling the action of said pawl, said inertia part having means for positively moving said pawl to releasing position.

12. A fire arm comprising a breech bolt, said breech bolt having a rotatable and a non-rotatable part, means for preventing rotation of said rotatable part, said means comprising a part carried by the non-rotatable part of said breech bolt.

In witness whereof, I have hereunto signed my name in the presence of two subscribing witnesses.

FRIEDRICH EICHHORN,
Administrator of the estate of Paul Mauser,
deceased.
